UNITED STATES PATENT OFFICE.

JOHN A. TYLER, OF LOS ANGELES, CALIFORNIA.

WATER HEATER.

Application filed August 15, 1927. Serial No. 213,039.

My invention relates to water heaters of the storage type as used in large building, and which consists of a tank having one or more heating units therein in the form of 5 coils of pipe to which steam is supplied as the heating medium.

In storage heaters of this character as heretofore proposed, the heating unit is removable from the tank to permit cleaning or 10 repair thereof, but its removal requires the laborious and time-consuming operation of uncoupling the steam supply pipes.

It is a purpose of my invention to provide in a hot water storage heater, an extremely 15 simple and inexpensive means by which the heating unit or coil can be readily removed or applied without the necessity of uncoupling the steam supply pipes, and when applied providing a steam-tight connection 20 with the supply pipes.

I will describe only one form of water heater embodying my invention and will then point out the novel features in claims.

In the accompanying drawings:

25 Fig. 1 is a view showing in side elevation and partly in section one form of water heater embodying my invention;

Fig. 2 is a view showing the heater in end elevation;

30 Figs. 3 and 4 are vertical sectional views taken on the lines 3—3 and 4—4 of Fig. 1; and

Fig. 5 is a central vertical sectional view of the header illustrated in Fig. 4.

35 In carrying out my invention, I provide a tank T to which the water to be heated is supplied by a pipe 15, and from which the heated water is discharged through a pipe 16. Within the tank are secured transverse 40 angle bars 17 and longitudinal angle bars 18, the latter being secured on the former and substantially coextensive in length with the tank. The bars 18 are spaced to accommodate a coil of pipe C, and to fixedly position the coil upon the transverse bars 17, all in a manner to support the coil centrally 45 adjacent the bottom of the tank.

The coil C constitutes part of a heating unit for the water in the tank T, the remainder of the heating unit comprising a header including a stationary part H and a movable part H'. The stationary part H consists of a cylindrical body secured at one end within an opening 19 at one end of the 55 tank. The outer end of the cylindrical body is normally closed by a hinged door 20 and

may be secured in closed position in any suitable manner.

Short lengths of pipe 21 and 22 extend through suitable openings in the cylindrical body as clearly illustrated in Figs. 4 and 5, and these pipes are in turn connected to supply pipes 23 and 24, respectively, provided with valves 25 and 26, respectively, provided for the purpose of controlling the 60 circulation of the heating medium to and from the header. It will of course be understood that the pipes 23 and 24 are connected to a source of supply such as a steam boiler (not shown), the steam being employed as 65 the heating medium.

The movable part H' of the header comprises a pair of companion elements 27 and 28 in the form of metal blocks having outer curved surfaces to conform to the contour 70 of the cylindrical body, and flat parallel inner surfaces. Each element is provided with L-shaped passages 29 into which is extended one end of the coil C, and the pipe is secured therein by threading as shown in 75 Fig. 5. The vertical portions of the passages extend to outer curved surfaces of the elements for communication with the pipes 21 and 22, so that the latter pipes are placed in communication with the ends of the coil 80 C. Suitable gaskets 30 and 31 are interposed between the elements 27 and 28 and the cylindrical body H, as well as between the latter elements and the door 20 in order 85 to prevent the escape of water as will be 90 understood.

The elements 27 and 28 are secured in the above described positions by means of an expander which, in the present instance, comprises a bolt 32, the head of which is welded to the inner side of the upper element 27 while the lower end of the bolt is countersunk within the inner side of the lower element 28 as indicated at 33. A nut 34 is threaded on the lower end of the bolt 95 so as contact with the flat side of the element 28. Thus, it will be seen that by rotation of the nut the bolt is fed upwardly through the nut thereby effecting expansion of the elements 27 and 28 into firm contact with the cylindrical body. The bolt may be secured in this expanded position by the provision of a lock nut 35 threaded on the bolt above the nut 34.

In practice, the coil C can be extended into 110 the tank through the cylindrical body H so as to be supported in the tank by the bars

17 and 18. In applying the heating unit the bolt 32 is adjusted to allow the elements 27 and 28 to occupy what may be termed a contracted position in order that they may 5 be inserted into the cylindrical body H and positioned as illustrated in Figs. 4 and 5, in which the passages 29 register with the inner ends of the pipes 21 and 22. Once the elements have been positioned as described, the 10 nut 34 can now be manipulated to cause the bolt 32 to expand the elements into firm contact with the cylindrical body and thus secure the passages and pipes in registering relation so that the supply pipes 23 and 24 15 are placed in circuit communication with the coil C. The door 20 is now secured in closed position and by opening the valves 25 and 26 steam or any other suitable heating medium is thus caused to circulate 20 through the coil C and thereby heat the water contained within the tank.

If it is desired to remove the coil for purposes of repair or cleaning, as is frequently necessary, the elements 27 and 28 can be 25 moved to contracted position by manipulation of the nut 34 thereby permitting withdrawal of the elements from the cylindrical body, and as the coil of pipe is connected to the elements it will be clear that with removal 30 of the elements the coil is likewise removed.

When removing the coil C from the tank T for the purpose of removing scale from the surface of the pipes of the coil or for 35 repairing the joints thereof, the expanding device can be actuated by rotation of the nut 34 to allow the blocks 27 and 28 to occupy a contracted position in which they can be readily removed from the cylindrical body 40 H together with the coil C. In removing the coil it is important to note that it is unnecessary to disconnect the pipes 21 and 22 from the cylindrical body H or the pipes 23 and 24 from the pipes 21 and 22, thus eliminating 45 the laborious and time-consuming operation of uncoupling the steam supply pipes as is necessary in similar apparatus as heretofore proposed.

Although I have herein shown and described only one form of water heater embodying my invention, it is to be understood that various changes and modifications may be made herein without departing from the spirit of the invention and the spirit and 55 scope of the appended claims.

I claim:

1. A water heater comprising a water tank, a heating unit in the tank, pipes for supplying a heating medium to the unit, and 60 expansible and contractible means for detachably connecting the heating unit to the supply pipes in a manner to permit disconnection and withdrawal of the heating unit from the tank independently of the supply 65 pipes.

2. In combination, a water storage tank, a coil of pipe, a header comprising a stationary part secured to the tank and constituting an entrance and exit opening through which the coil of pipe can be extended into or withdrawn from the tank, a movable part secured to the coil of pipe and insertable into the stationary part, and supply pipes for supplying a heating medium to the header, said movable and stationary parts 70 having coacting passages effecting communication between the coil of pipe and the supply pipes, said movable part being expansible to secure its passages in registering relation to the passages of the stationary part. 75

3. In a hot water storage heater, a tank, a coil pipe in the tank, pipes for circulating a heating medium through the coil of pipe, and a header providing communication between the pipes and the coil of pipe, said header being expansible to secure the pipes 85 in communication with each other and contractible to permit removal of the coil of pipe from the tank without disconnecting the supply pipes. 90

4. In a hot water storage heater as embodied in claim 3 wherein the header comprises a tubular body secured to the tank and through which the coil of pipe can be extended into or withdrawn from the tank, 95 companion elements removably fitted in the body and connected to the ends of the coil of pipe, passages in the body and companion elements, and an expanding device interposed between the companion elements for moving the latter into firm contact with the body to secure the passages in registering relation and to permit contraction of the elements to allow their withdrawal from the body. 100

5. A hot water storage heater comprising 105 a tank having an opening therein, a tubular body surrounding the opening and formed with passages, supply pipes connected to the passages, blocks in the tubular body having passages adapted to communicate with the passages of the body, a coil of pipe secured to the blocks and communicating with the passages thereof, said coil being of such dimensions that it may be passed through the tubular body into or out of the tank, and an 110 expander interposed between the blocks for moving and securing the blocks in fixed position within the tubular body with its passages in registering relation to the passages of the body. 115

6. A hot water storage heater as embodied 120 in claim 5 wherein the expander comprises a bolt secured to one of the blocks, and a nut on the bolt engageable with one of the blocks so that when rotated on the bolt it will operate to spread the blocks. 125

7. A hot water storage heater as embodied 130 in claim 5 wherein the expander comprises a bolt secured to one of the blocks, a nut on the bolt engageable with other of the blocks

so that when rotated on the bolt it will operate to spread the blocks, and means for securing the nut against rotation on the bolt.

8. A hot water storage heater as embodied in claim 5 wherein means is provided within the tank for supporting the coil of pipe in definite position therein.

9. A hot water storage heater as embodied in claim 5 wherein means is provided within the tank for supporting the coil of pipe in definite position therein, said means comprising intersecting bars, certain of which are spaced to accommodate the coil of pipe and longitudinally align with respect to said

15 opening.

10. A header for water heaters comprising a stationary part adapted to be secured to a tank and constituting an entrance and exit opening through which a pipe can be extended into or withdrawn from the tank, 20 and a movable part adapted to be secured to the pipe and insertable into the stationary part, said movable and stationary parts having coacting passages adapted to effect communication between said pipe and supply 25 pipes, the said movable part being expandible to secure its passages in registering relation to the passages of the stationary part.

JOHN A. TYLER.
